UNITED STATES PATENT OFFICE

WILLIAM MCCOY, OF ZANESVILLE, OHIO, ASSIGNOR TO AMERICAN ENCAUSTIC TILING COMPANY, LTD., OF NEW YORK, N. Y., A CORPORATION OF NEW YORK

TILE EXHIBITOR

Application filed September 21, 1927. Serial No. 221,125.

This invention is an apparatus for exhibiting and displaying commodities of one kind or another, but while it possesses certain characteristic features rendering it useful for exhibiting tiles now used so generally in the construction of dwellings, office buildings and other structures, it is to be understood that I do not limit or restrict the apparatus for the display of the specified commodity.

Persons skilled in the sales and installation of tiles for walls, floors and other parts of a dwelling, building or the like, are fully cognizant of the fact that such tiles are characterized by the presence on their surfaces of a decorative ornamentation which frequently takes the form of a glaze in different colors, or of glazes in different shades of the same general color. Heretofore, the common practice in the display of tiles is to exhibit a number of differently colored tiles, or tiles bearing different shades of the same color, on a panel or series of panels, all of which are exposed at one time to view in a show room. Such display of all the tiles at one time for inspection renders it quite perplexing to the customer to decide upon the tiles suited to a particular purpose in a room the decoration of which may be or is in a certain pattern, or according to a definite color scheme, and such display of all the tiles may be and frequently does lead to mistakes in the selection of the tiles to be ordered, and which such indiscriminate display is from one standpoint a convenience for the customer, yet from other standpoints it leads to confusion and perplexity in the selection of tiles.

According to the present invention, provision is made by a series of panels for the display of different tiles, or differently colored tiles, all the tiles of one color being carried by one panel, and said similarly colored tiles being mounted on the panel in the same way as they would appear in a wall, floor, or other surface. Thus the different panels carry differently colored tiles, or tiles of different patterns, and said panels are adapted to be brought into view at will, one after the other, for inspection by the customer, so that when any one panel is exposed to view all the other panels and their tiles are concealed from view.

By this structure and mode of procedure, the tiles are displayed for inspection, comparison and selection, avoiding confusion and error, and facilitating the labor, whereby economy of time is attained.

55

In a practical form of the invention, two series of panels are used, the panels of one series being normally hid from view at one side of a large viewing opening provided in an appropriate housing, whereas the panels of the other series are hid from view at the opposite side of said opening of said housing, but in the display of the tiles to the customer, either panel of either series may be pulled out of the concealing space and brought to rest in the plane of the viewing opening so as to expose the tiles on that particular panel for inspection. The panels are positioned vertically, in compact relation, and usually they are slideable horizontally so as to be guided for movement in determined paths with reference to the viewing opening. It is preferred, although not essential, to illuminate the apparatus in a way to throw light from the source of illumination on the tiles, and, further, to provide a curtain or curtains to be drawn across the viewing opening for concealing the tiles from view. For certain effects, the apparatus may take the form of a miniature "theatre", although this is optional.

70

Other functions and advantages of the invention will appear from the following description taken in connection with the accompanying drawings, wherein

85

Figure 1 is a front view in elevation of one form of the apparatus illustrating the invention as embodied in an appropriate housing having the semblance to a theatre proscenium in miniature.

90

Figure 2 is a front elevation, on a somewhat larger scale, showing a skeletonized housing or framework for the operating means associated with two series of panels positioned normally in concealed relation to a viewing opening and at opposite sides thereof.

95

Figure 3 is a vertical sectional elevation through the apparatus of Figure 2, taken substantially centrally thereof.

100

Figure 4 is a detail front view of one of the panel carriers and a single panel mounted thereon, illustrating partly some of the tiles on said panel.

5 Figure 5 is a detail view illustrating guiding means at the bottom of one panel carrier for directing the latter in a definite path of movement.

10 Figure 6 is a detail cross sectional view illustrating one form of light housing employed at the front of the apparatus, an incandescent lamp being shown in dotted lines.

15 Various operating parts and devices of my exhibitor or display apparatus are supported by and within an appropriate housing or framework, indicated generally in the drawings by the reference character A. Such framework is of skeleton formation, with a large viewing opening, B, extending from front to rear, and at the respective sides of said opening are positioned the panels or panel carriers, two series of which are usually employed, one series being indicated at C, and the other series at D.

25 Obviously, the particular form of the framework A to be used may be embodied in various constructional forms, one of which is shown in drawings as illustrative of the invention. As therein shown, the framework 30 comprises vertical members a, horizontal members a', and a flooring a², said members a, a', and flooring a², being of any desirable material and assembled as determined by a skilled constructor. At the front of the apparatus, the framework is concealed by appropriate means, but in the form selected for illustration, a proscenium arch, E, is used with a viewing opening in line with the space B, and across which opening may be drawn a 35 curtain or drapery F for shutting off the view.

The proscenium may be ornamented by the use of tile work on the front thereof, as at e in Figure 1, or other ornamentation may be resorted to for lending to the attractiveness 45 of the display. Again, the type of curtain or drapery F may be altered as desired, but as shown there are a plurality of curtains, supported by rings f, the latter being slidable at will on a horizontal curtain rod f', concealed from view by a housing f², attached to the framework or to the proscenium, in a desirable manner.

50 The panels C, D, are in two series, the panels C of one series being concealed from view ordinarily at one side of the viewing opening B, whereas the panels D of the other series are concealed from view usually at the opposite side of said opening B, see Figure 2; but it is to be noted that at the will of the 55 salesman, either panel of either series C or D may be shifted from the out-of-service position of Figure 2 to a place within or across the viewing opening B, as represented in Figure 1, whereby the only panel in the line of vision is that one which occupies the view-

ing opening, as a result of which mode of displaying the tiles, the view of the customer is restricted or limited to the tiles on the one panel thus temporarily displayed. The panels C, D, are similar in construction, so that a 70 description of one panel will serve for all the others.

75 Referring now to Figures 3, 4 and 5, the panel comprises a plurality of elongated bars or rods c, hangers c', a trolley c², an overhead track c³, a foot rail d, and guide rollers d'. The rods or bars c extend vertically within the framework, and are parallel to provide a 80 surface against which a panel board is fitted in compact relation to said bars or rods. This panel board is composed of any thin substantial material suitable for the purpose, such, for example, as that composite material known in the building trades as "beaver board." The panel board indicated at G is 85 attached fixedly in a desirable manner to the bars or rods c of the panel carrier; as shown in Figure 5, the lower ends of the bars or rods are bent forwardly and then upwardly at g to provide a seat in which is fitted the lower 90 marginal portion of the panel board, whereas the upper portion of said panel board is clamped against the bars or rods by bolts g'. The panel board is thus seated on the rods or 95 bars and clamped thereto so as to impose the weight of the panel board and the tiles attached thereto upon the rods or bars, and said panel board is readily demountable from said rods or bars by loosening the bolts g' and lifting the panel board out of the seat g, thus 100 allowing panel boards with different tile assemblies to be interchanged with facility. The hangers c' are attached to the upper ends of the bars or rods, and these hangers are equipped with rollers or wheels c² acting as 105 a trolley for the free sliding movement of the panel as an entirety. The trolley slides on a trackway c³ of suitable form fixed in an overhead position to the framework, thus making 110 provision for suspending the panel in a way to adapt it for sliding movement to and from the service position. A foot rail d is fastened to the bent seat portion g of the parallel rods or bars c, and this foot rail is provided with a channel or groove d² open at the underside of the foot rail. A plurality of guide rollers d' are fixedly attached by screws d³ to the floor a², see Figure 5, and these guide 115 rollers are in the vertical plane of the overhead trackway c³, or substantially so (see Figure 3). The panel carrier is thus suspended by the trolley and guided by the rollers to preclude swaying movement of the panel, thus directing the movement of the panel in a determined path, and overcoming 120 a tendency of one panel to strike or rub against an adjacent panel or panels, whereby dislodgment of the tiles is precluded. It is desirable to employ a member H at the top 125 part of the panel carrier, serving as a spacer

and coupling permanently attached to the bars or rods *c*, thus retaining said bars or rods in a determined relation to each other when dismounting and interchanging the 5 panel boards. Said member *H* may be composed of the same material as the panel board, but as it is above the line of vision through the opening *B*, it is not ordinarily required to be supplied with tiles to be displayed.

10 Provision is made for the illumination of the display on the panels when occupying the viewing opening *B*. Accordingly, there is provided a light housing *I*, one on each side of the viewing opening, and within said housing is positioned a series of electric lamps *j*. Each light housing is in the form of a channeled casing, approximately V-shaped in horizontal cross section, and said housing is erected vertically on the proscenium front *E*, 20 at one edge of the opening *B*, see Figures 2 and 3. The light housings *I* at the opposite sides of the opening are fixedly secured in position for the open sides of the channels to face toward the interior of the exhibitor, and, 25 if desired, these housings are provided with mirrored or reflecting surfaces, at *i* in Figure 6, so as to throw the rays of light emanating from the lamps against the tiles displayed on the panel when the latter is moved into the 30 service position across the viewing opening. It is apparent that the electric lamps should be wired for the supply of electric current from an available source of supply; as shown, a switch box *I'* is provided on one of the 35 housings (see Figure 2), with appropriate switches for controlling the flow of current to the lamps in the respective housings *I*.

In my exhibitor the housing is provided with two storage compartments, one at either 40 side of the viewing opening, and the trackways at top and bottom of the housing extend crosswise of the two compartments and said viewing opening. There are at least two panel carriers on each trackway, and said 45 panel carriers on each trackway are in the path of each other. This provision of the storage compartments at the opposite sides of the viewing opening increases the capacity of the exhibitor for the storage of panels and 50 panel carriers, two series being employed, one series for each compartment. By using trackways which extend crosswise of the compartments and the viewing opening I am enabled to utilize the panel carriers on each 55 trackway to attain a function new in this art, i. e. one panel carrier acts as a stop to the sliding movement of the other panel carrier on the same trackway, and thus either panel carrier is arrested when it reaches a service position 60 at the viewing opening whereby any one panel cannot move out of its compartment too far beyond the viewing opening because the sliding movement of one panel to the service position for exposure through the 65 viewing opening is arrested automatically by

contact with the other panel on the same trackway.

The commodity, such as tiles, are attached to the face of each panel board by any suitable means, such as by an adhesive. It is preferred to display tiles in the manner in which they are to appear in a wall or floor, so that in the display to the view of a customer, the tiles present the appearance they occupy when installed. Thus in Figure 2, each panel *C*, *D*, is shown as having tiles assembled as in a mosaic flooring, but the assemblage and character of the tiles will be modified and changed on the several panels. In the case of wall tiles of a particular color, all the tiles of that particular color are attached to a panel board in simulation of a floor or wall as the case may be. Differently colored tiles are used on the different panels, and it is feasible to employ different shades of the same color on different panels. As shown, twelve panels are employed in the series *C*, and a similar number of panels are provided in series *D*, making provision for a total display of twenty-four different kinds of tiles, all arranged compactly within a space of small dimensions, and enabling the different kinds of tiles to be brought into view with facility, whereby confusion is avoided and the customer is able to make selections as to appearance and color to the best advantage. Of course, the number of panels may be increased or decreased as found expedient, but the essential feature is that there is brought into view of the customer tiles of a particular color or character, displayed in the order they appear in a wall or floor. Each panel is moved with ease from the out-of-service position to the service position bounded by the viewing opening, the draperies and lighting facilities adding to the attractiveness of the display, and confining the view of the spectator to the special or selected tiles under observation and inspection. The illumination may be turned on or shut off as required, and the draperies may be closed to exclude dust and dirt, or they may be opened to permit access to the panels or either of them. The exhibitor is installed in a show room wherein is displayed a variety of tiles in different shapes, grades, colors, and surrounded with other factors for the consideration of the purchaser, but in the final analysis, the display of tiles by the exhibitor affords the safest criterion for the determination and selection of the tiles to be purchased and used.

Having thus fully described the invention, what I claim as new and desire to secure by Letters Patent is:

1. In a tile exhibiting and displaying device, a panel carrier comprising a plurality of rods positioned vertically and in side by side relation, each rod having a bent lower end portion affording a seat, a member fixed to the rods and connecting the same, and

hangers fixedly attached to the upper ends of said rods, in combination with a housing provided with storage compartments and with a viewing opening, trackways extending crosswise of the compartments and said opening, said hangers being movable on said trackways for limiting the panel carriers to movement in rectilinear paths, there being at least two panel carriers on each trackway and 10 said panel carriers being positioned one in the path of the other whereby either panel carrier occupying a concealed position functions as a stop to the other panel carrier on the same trackway when the latter panel carrier occupies a service position exposed through the viewing opening.

2. In a tile exhibiting and displaying device, a panel carrier comprising a plurality of rods, a foot rail attached to said rods and connecting the lower ends thereof, said foot rail being provided with a groove, in the lower side thereof, and a member connecting the rods at the upper portions thereof, in combination with a housing provided with storage compartments and with a viewing opening, trackways extending crosswise of the compartments and said viewing opening, there being at least two panel carriers on each trackway and said panel carriers being one 20 in the path of the other for one panel carrier occupying a concealed position to function as a stop to the sliding movement of the other panel carrier when shifted on the same trackway to a service position exposed through 30 the viewing opening.

3. A tile exhibiting and displaying means, comprising a housing provided with storage compartments and with a viewing opening, trackways extending across the compartments and said opening, a panel carrier formed at its one end with a seat and provided with means intermediate its ends for clamping a tile panel on the panel carrier, hangers mounted on the other end of said 40 panel carrier, said hangers being movable on said trackways for guiding the panel carrier in a rectilinear path, there being at least two panel carriers on each trackway and said panel carriers being positioned one in the path of the other whereby a panel carrier occupying a concealed position functions as a stop to the other panel carrier on the same trackway when the latter panel carrier occupies a service position exposed through the 50 viewing opening.

4. A tile exhibiting and displaying device comprising a housing, trackways at the top and bottom of said housing, said trackways extending across the housing, panel carriers 60 each being provided with a seat and clamping means for rigidly securing a tile panel in position on said panel carrier, a grooved foot rail mounted on one end of each of the panel carriers, each of the panel carriers being provided with trolleys slidably mounted on the

trackways at the top of the housing, the grooved foot rail being adapted to be guided by the trackway on the bottom of the housing, said panel carriers being movable on said trackways for guiding the panel carriers in rectilinear paths. 70

5. In a tile exhibiting and displaying device, a panel carrier comprising a plurality of rods positioned vertically and in side by side relation, each rod having a bent lower end portion affording a seat adapted to support a tile panel, a member fixed to the rods and connecting the same, hangers fixedly attached to the upper ends of said rods, and securing means on said panel carrier adapted to engage a portion of a tile panel to clamp the same in position on said seat. 75

6. In a tile exhibiting and displaying device, a panel carrier comprising a plurality of spaced rods in side by side relation, each rod having a bent lower end portion affording a seat and a clamping means intermediate its ends, a member fixed to the rods and connecting the same, and hangers fixedly attached to the upper ends of said rods, said seat being adapted to receive a tile panel, and said clamping means being adapted to clamp a tile panel on said carrier. 80

In testimony whereof I have hereto signed my name this 19th day of September, 1927.

WILLIAM McCOY.
